ROLLER DEVICE

Charles J. Rey, Wellston, Mo.

Application October 31, 1941, Serial No. 417,393

4 Claims. (Cl. 280—44)

This invention relates to a roller device particularly adapted for use in connection with any article for which a firm support is required during use of the article or machine but which must be moved to different positions or locations from time to time.

An object of the present invention is to provide a roller device having castors and an easily operated mechanism for moving the castors into and out of service position so that the article or machine may be handled by a single operator regardless of size or weight.

A further object is to provide a device of this character which may be installed on articles or machines now in use, such as table power saws, washing machines, sheet metal shears, long tables and many other articles and machines, or may be readily built into such articles or machines during course of construction.

A further object is to provide a device of this character which will be formed of a few simple strong and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims, without departing from the spirit or sacrificing any of the advantages of the invention.

In the accompanying drawings forming part of this specification,

Figure 1 is a side elevation of a roller device constructed in accordance with the invention, shown in released position on a work table.

Figure 2 is a side elevation of the work table and roller device, showing the roller device in operative or service position to permit the table to be rolled to a different location.

Figure 3 is a horizontal sectional view taken on the line 3—3 of Figure 1.

Figure 4 is a vertical sectional view taken on the line 4—4 of Figure 2.

Referring now to the drawings in which like characters of reference designate similar parts in the various views, 10 designates a table top and 11 designates the supporting legs of a table, used as an example of an article to which the roller device may be applied.

The roller device, in accordance with the invention, comprises levers 12 secured to the inner sides of the legs 11 by leaf hinges 13, the ends of the levers to which the hinges are secured being

sloped as shown at 14 to permit the levers being swung upwardly to inclined released position, or to permit the levers being swung to the horizontal or operative position. Each lever is equipped on the bottom, near the hinged end, with a castor 15 which is adapted to engage the floor when the lever is in horizontal position and elevate the respective leg 11 above the floor and thereafter support the weight of the table while the table is being rolled on the castors to a new location. In operative or service position the levers on the same end of the table are aligned and abut each other at the free ends, see Figure 2.

As best shown in Figure 4, a pair of guide bars 16 are secured to the legs 11 at the same end of the table and engage the sides of the levers 12 to prevent the lateral displacement of the levers and to guide the levers during rocking movement thereof from the released position shown in Figure 1 to the operative position shown in Figure 2. Helical springs 17 are secured at the upper ends to the legs 11 and are secured at the lower ends to the levers 12 and normally support the levers in raised position.

25 A reinforcing frame and mechanism carrying member is secured to the legs 11 and comprises longitudinally disposed braces 18 and transversely disposed braces 19, secured to the inner faces of the legs 11 above the levers 12.

30 The two levers 12 on the same end of the table are bridged by, and contact with, the head 20 of a plunger 21 when the levers are in raised position, see Figure 1. The plunger is substantially rectangular in cross section as shown at 22, see Figure 3, and is slidably fitted to move vertically in an opening of similar shape formed in a guide 23 which is secured to the outer face of the respective transversely disposed brace 19. The springs 17 normally hold the plungers 21 in raised position to project above the guides 23 due to contact of the levers 12 with the heads 20 of the plungers, see Figure 1.

35 A shaft 24 is rotatably mounted in openings 25 formed in the transversely disposed braces 19. 45 The ends of the shaft project beyond the braces and are equipped with cam disks 26 which are secured eccentrically thereto. The cam disks are superposed above the plungers 21 and are spaced from the transversely disposed braces 19 by 50 spacing washers 27, see Figure 4. A lever 28 is fixed to the shaft for rotating the shaft.

The lever 28 normally abuts the top edge of one of the longitudinally disposed braces 18 and in this position of the lever the low side of each 55 cam disk 26 is presented to the respective

plunger. When the lever 28 is rotated through an arc of about 180 degrees from the position shown in Figure 1 to the position shown in Figure 2 the high side of each cam disk will be presented to the respective plunger to move the plunger downwardly so that the plunger head rocks both respective levers 12 to service position for elevating the table above the floor on the castors 15.

A stop 29, see Figure 4 is secured to the inner face of one of the transversely disposed braces 19 and limits rocking movement of the lever to operative position.

Since the operation of these parts has been described as the description of the parts progress it is thought the invention will be fully understood without further explanation.

What is claimed is:

1. A roller device comprising a pair of castor carrying levers disposed between and hinged to the legs of a table or other machine, springs connected to the legs normally supporting the levers in raised position to dispose the castors out of contact with a floor, a frame on the legs above the levers, guides on the frame, plungers mounted to slide vertically in the guides having heads contacting the free ends of the levers, a

shaft rotatably mounted on the frame, cams fixed to the shaft contacting with the upper ends of the plungers, a lever for turning the shaft to cause the cams to lower the plungers against the pull of the springs to swing the levers downward and dispose the castors below the legs, and guides fixed to the legs and engaging the levers to hold the levers against accidental lateral movement.

2. A structure as of claim 1 and in which the head of each plunger bridges the free ends of the respective pair of castor carrying levers disposed on the legs of the same end of the table or machine as the plunger, and in which said springs constantly hold the levers in contact with the lower side of said head.

3. The structure as of claim 1 and in which the hinge of each lever is a leaf hinge having one leaf thereof secured to a sloped outer end of the corresponding lever to permit the lever to swing upward until the leaves of the hinge engage each other.

4. The structure as of claim 1 and in which said springs are helical springs connected to the legs and to the free ends of the levers.

CHARLES J. REY.
